DRY MIXES FOR USE IN ELECTROLYTIC RECORDING

Harold G. Greig, Princeton, N. J., assignor to
Radio Corporation of America, a corporation
of Delaware

No Drawing. Original application November 4,
1944, Serial No. 562,032. Divided and this application
September 26, 1947, Serial No. 776,411

4 Claims. (Cl. 204—2)

1

The present invention relates to dry stable mixes for use in preparing solutions for the electrolytic preparation of colored images on a traveling web or band which for simplicity may be referred to as a receiver. This application is a division of my co-pending application Serial No. 562,032, filed November 4, 1944, now Patent No. 2,442,596, granted June 1, 1948.

The production of color image records by electrolyzing a solution containing a diazotizable amine, a nitrite, an electrolyte such as sodium chloride, potassium chloride and the like and a coupler, is disclosed in Solomon U. S. P. 2,306,471. In my co-pending application Serial No. 562,033, filed November 4, 1944, now Patent No. 2,493,963, granted Jan. 10, 1950, and entitled "Electrolytic Recording," it is suggested that there be substituted for the amine and nitrite of such solution a stabilized diazo amino compound. Manifold advantages, including an improved stability of the records to light, are obtained when operating in this way. It has been found that these two methods are the most efficacious for electrolytically producing color image records especially in facsimile recording. By the term "facsimile recording" as used herein is meant not only the reproduction on the receiver of a pre-existing subject, but also the reception of subject-matter in the process of creation or formation.

The production from dry mixes of the electrolytic recording solutions with which the receiver is treated in these methods has manifest advantages. If the dry mix be storage stable, it can be prepared in bulk and stored for a considerable period of time. Furthermore, it can be shipped to whatever destination desired at a much lower cost than the water solutions. The production of dry mixes suitable for use in these processes has accordingly been a desideratum in this art.

The couplers which have been found to give best results in the methods previously outlined are naphthol sulfonic acids, of which chromotropic acid is an example. This acid is usually sold in the form of its mono-sodium salt. This salt is acid and if incorporated into a dry mix containing a diazotizable amine and a nitrite or a stabilized diazo amino compound, it would induce premature diazotization and coupling in the first instance, and premature splitting of the diazo amino compound and coupling in the second

instance. If, on the other hand, the alkalinity of such compounds be increased to avoid such premature action by the utilization of the usual alkalies such as sodium hydroxide, sodium carbonate, potassium hydroxide, and the like, it is found that the records obtained suffer because of a poor shade of the images and because of the instability of the background to light. It has therefore been considered preferable, up to the present time, to prepare fresh solutions for electrolytic recording rather than to produce dry mixes which can be stored and shipped for use at a time in the future despite the advantages inherent in the latter course of action.

15 I have now discovered that the objections to the dry mixes previously proposed can be avoided by utilizing in such dry mixes as the coupling compound a naphthol sulfonic acid, either mono- or poly-, in which at least one of the sulfonic acid groups is neutralized by an alkyloamine. The alkyloamine forms a salt of the naphthol sulfonic acids. Such salts are stable and dissolve in water in the concentrations in which they are used in electrolytic recording to give a pH of 20 approximately 9.5. The alkalinity induced by using the alkyloamine prevails during storage so that no premature diazotization or splitting of the diazo amino compound with resulting coupling takes place. Due to the stability of such 25 compounds or to some other as yet unascertained property thereof, solutions in water or another suitable solvent such as alcohol of dry mixes containing the same, produce on electrolysis, dark image records the background of which has a 30 much higher permanence to light than records obtained where the alkalinity has been produced by resort to the usual alkalies.

It is accordingly an object of my invention to produce dry mixes for the production of electrolytic recording solutions wherein the coupling component is a naphthol sulfonic acid in which 35 at least one sulfonic acid group has been neutralized with an alkyloamine.

It is a further object of my invention to produce dry mixes for the production of electrolytic recording solutions wherein the coupling compound is a naphthol polysulfonic acid in which at least one sulfonic acid group has been neutralized with an alkyloamine.

It is a further object of my invention to pro-

duce storage stable dry mixes containing a primary aromatic amine, a nitrite, an electrolyte and a naphthol sulfonic acid as the coupling compound in which at least one sulfonic acid group has been neutralized with an alkylolamine.

It is a further object of my invention to produce storage stable dry mixes of a stabilized diazo amino compound, an electrolyte and as the coupling compound a naphthol sulfonic acid at least one of the sulfonic acid groups of which has been neutralized with an alkylolamine.

It is a further object of my invention to produce records by electrolyzing a solution containing a source of diazonium ions, an electrolyte, and as a coupling compound a naphthol sulfonic acid in which a sulfonic acid group has been neutralized with an alkylolamine.

It is a further object of my invention to produce dry mixes for forming electrolytic recording solutions in which the coupling compound is chromotropic acid, the sulfonic acid groups of which have been neutralized by an alkylolamine.

Further objects of my invention will appear as the description proceeds.

It has been stated the dry mixes of the present invention contain either a diazotizable amine and a nitrite or a stabilized diazo amino compound. In other words, the diazonium ions which react with the coupling component are produced by the action of the facsimile recording current on the diazotizable amine and the nitrite on the one hand and the diazo amino compound on the other hand. The diazotizable amine or the aryl amine from which the stabilized diazo amino compound is produced may be any of the diazotizable aryl amines utilized in the azo dyestuff art. Examples of such amines are given in the aforesaid Solomon patent and in my aforesaid co-pending application Serial No. 562,033 and entitled "Electrolytic Recording," to which attention is directed. Such amines are, for example, naphthionic acid, 4,4'-diamino-diphenyl-2,2'-disulfonic acid, 4,4'-diaminodiphenyl 3,3'-disulfonic acid, 4,4'-diaminodiphenylamine-2-sulfonic acid, orthotolidine-2,2'-disulfonic acid, alpha-naphthylamine-4,8-disulfonic acid, alpha-naphthylamine-5-sulfonic acid, o-anisidine-4-sulfonic acid, and the like. These amines when used in the form of the stabilized diazo amino compounds may have their diazonium compounds stabilized with an aliphatic amine such as ethanolamine, diethanolamine, carcosine, diisopropanolamine, dimethylamine, diethylamine, and the like, by an aromatic amine which does not readily couple, such as 4-sulfo-2-aminobenzoic acid, 2-methyl-amino-4-sulfobenzoic acid and the like, or by a heterocyclic amine, such as alpha-carboxy pyrrolidine, alpha-1-alpha-2-dicarboxy pyrrolidine, piperidine, carbazole and the like.

The stabilized diazo amino compounds are prepared by diazotizing the primary aromatic amine and reacting the resulting diazonium compound in an alkaline solution with one of the aforesaid organic amines which does not easily couple to form an azo dye. It is advisable when producing the stabilized compound, to use an excess of the stabilizing amine over the quantity theoretically necessary to produce the stabilized diazonium compound since otherwise difficulties may be encountered in the stability of the records to light.

As the coupling component there may be used any naphthol sulfonic acid at least one sulfo group of which has been neutralized with an al-

kylolamine. Such compounds have the following formula, assuming that diethanolamine is the neutralizing agent:

wherein n is 1 or 2, m is 1 to 3, and R is hydrogen, or a substituent group such as amino, acetyl, and the like. As examples of such naphthols, the alkylolamine salts of which are contemplated by the present invention, may be mentioned

- 25 1-naphthol-6-sulfonic acid
- 2-naphthol-8-sulfonic acid
- 1-hydroxy-8-acetylarnino naphthalene-3,6-disulfonic acid
- 1-hydroxy-8-amino naphthalene-3,5-disulfonic acid
- 30 1-hydroxy-8-amino naphthalene-6,7-disulfonic acid
- 1,8-dihydroxynaphthalene-3,6-disulfonic acid
- 1-hydroxy-8-amino naphthalene-3,6-disulfonic acid
- 35 1-hydroxy naphthalene-3,6-disulfonic acid
- 2-hydroxy-naphthalene-3,6-disulfonic acid
- 1,7-dihydroxy naphthalene-3,6-disulfonic acid
- 2-hydroxynaphthalene-6,8-disulfonic acid
- 40 1-hydroxynaphthalene-3,6,8-trisulfonic acid
- 1,3-dihydroxynaphthalene-5,7-disulfonic acid
- 1,5-dihydroxynaphthalene-2,7-disulfonic acid
- 1,5-dihydroxynaphthalene-3,7-disulfonic acid
- 1,7-dihydroxynaphthalene-3,7-disulfonic acid
- 45 1-hydroxy-7-amino naphthalene-3,6-disulfonic acid

and the like. Best results, however, have been secured with the salts of chromotropic acid and the use of the salt of this acid represents the preferred embodiment of my invention.

The preparation of the alkylolamine derivative of the coupling compound may be carried out by dissolving the alkylolamine in a volatile, inert solvent such as alcohol, and reacting the coupling component with the solution of the alkylolamine. Upon heating to a temperature of 65 to 70°C., the excess alkylolamine is removed with the alcohol. It might be noted that as such a solvent, morpholine may also be employed and by proportioning the quantities of the alkylolamine and the morpholine a mixed alkylolamine-morpholine salt is obtained.

It has been previously pointed out that at least one of the sulfonic acid groups of the coupling component is neutralized with the alkylolamine. If the naphthol sulfonic acid employed is a mono-sulfonic acid, only the monoamine salt is formed, in which case the preparation is effected by using 1 mol of the naphthol sulfonic acid with at least 1 mol of the alkylolamine. Where the coupling component is a polysulfonic acid, the ratio of the reactants will vary depending upon the particular naphthol polysulfonic acid selected and the results desired. If, for instance, a di-sulfonic acid such as chromotropic acid is used,

a monoamine salt may be prepared by using 1 mol of the sulfonic acid for each mol of the alkylolamine. If, however, the di-salt is desired, at least 2 mols of the alkylolamine are used for each mol of the chromotropic acid. Similarly, if the polysulfonic acid is a trisulfonic acid, by adjusting the proportions in the manner noted, the mono-, di- or triamine salt may be produced.

It is also possible to produce salts of the naphthalene polysulfonic acids in which one sulfonic acid group is neutralized with an alkylolamine and another group is neutralized by means of another radical. Thus, by using a naphthalene disulfonic acid such as chromotropic acid, with 1 mol of an alkylolamine and 1 mol of morpholine, the mixed alkylolamine-morpholine salt results.

The dry mixture which is used, irrespective of the source of the diazonium compound, must contain an electrolyte. The electrolyte is preferably sodium chloride, although other common electrolytes such as potassium chloride, sodium bromide and the like may be utilized with equally good results.

The preferred pH of the solution resulting from dissolving the dry mixture in water is between 9.5 and 11.5. In some instances, the alkalinity afforded by the salt of the coupling agent will not give the pH which is optimum for the component used. In that case, it is desirable to add a very small amount of an inorganic alkali such as sodium hydroxide, potassium hydroxide or the like. The quantity of this agent required will usually be from 1 to 2 grams per liter of the recording solution.

Other ingredients may be incorporated in the dry mix and in particular a wetting agent to facilitate the impregnation of the carrier by the solution. Suitable wetting agents are alkyl naphthalene sulfonic acids, for example, butyl naphthalene sulfonate and the like, the condensation product of a sulfonated benzene with chlorinated kerosene, said compound having the formula

where R represents the hydrocarbon radicals present in kerosene (see U. S. P. 2,220,099), and sarcosine and taurines, the nitrogen atom of which is acylated with a high molecular weight fatty acid, for example, oleic, palmitic and the like. The wetting agent will usually be present in an amount ranging from .05 to about 1 gram per liter of solution.

The invention will be further understood from the following examples, but it is to be remembered that these examples are illustrative and not limitative.

Example I

.06 gram mols of diethanolamine are dissolved in 30 cc. of ethyl alcohol.

.03 gram mols of dry, finely ground chromotropic acid is slurried from one-half hour with this ethyl alcohol solution. The product is then dried at a temperature of 65 to 70° C. There is thus obtained a purple-gray product having a dry weight of 21.42 grams and which is the di-salt of diethanolamine chromotropic acid.

.2 gram mol of diethanolamine salt of chromotropic acid, .4 gram mol of the diazo compound from diazotized naphthionic acid and diethanolamine,

3.3 grams of the condensation product of naph-

thalene sulfonic acid with chlorinated kerosene, 163.8 grams of sodium chloride, and

8.2 grams of sodium hydroxide are thoroughly ground and mixed together to produce a uniform dry product.

74.5 grams of this mixture are dissolved in a liter of water for the preparation of a facsimile recording solution. This solution has a pH of 10.1. Records produced with such a solution are

10 a dark blue purple, the background of which has a high stability to light.

The diazo amino compound from diazotized naphthionic acid and diethanolamine referred to above is obtained as follows:

15 .5 gram mol of sodium naphthionate are dissolved in approximately 750 cc. of water to which sufficient sodium hydroxide is added to make the solution alkaline to brilliant yellow test paper.

.5 gram mol of sodium nitrite is then added and 20 the solution is run under rapid agitation at a temperature of 5 to 10° C. into a solution of 140 cc. of 38% hydrochloric acid and 750 cc. of water and ice. Diazotization is complete almost as soon as the solution is added and the diazonium com-

25 pound, which is quite insoluble, precipitates out as a thick, creamy slurry. Stirring is continued for one hour to obtain the product in a form in which it is more easily filtered. Filter cake obtained upon filtration is reslurried in approxi-

30 mately 500 cc. of water until a smooth paste is obtained. This paste is added slowly at 10 to 15° C. over a two-hour period with rapid agitation to a solution of 125 cc. of diethanolamine in 250 cc. of water while maintaining a temperature of 10

35 to 15° C. in an ice bath to minimize decomposition.

The reaction is complete when all the diazonium compound has been added. The resulting solution is amber in color and may stain paper

40 with a reddish tint. It must be alkaline when tested with brilliant yellow test solution.

2 grams of sodium hydrosulfite are added and the solution stirred for one hour at room temperature to clear away the red-staining impurities.

45 20 grams of activated charcoal are incorporated and the temperature raised to 50 to 55° C. for 1/2 hour for the purpose of further clarifying the solution and to remove basic impurities. Sodium chloride is then added to precipitate the diazonium compound which is filtered off, washed and dried.

Example II

.06 mol of monoethanolamine are dissolved in 55 30 cc. of ethyl alcohol.

03 mol of chromotropic acid in a dry, finely ground condition is slurried for one-half hour with this ethyl alcohol solution. The product obtained upon drying at 65 to 70° C. has a dry weight equal to 18.74 grams and is the di-mono-

ethanolamine salt. It is a dark gray in color.

This salt of monoethanolamine is employed in the same manner as the diethanolamine treated chromotropic acid of Example I to give a dry mix suitable for electrolytic recording solutions.

65 Blue-purple records of a good background stability to light are obtained upon submitting a receiver treated with a water solution of the dry mix to the action of an electrolytic current.

Example III

.06 mol of triethanolamine are dissolved in 20 cc. of ethyl alcohol.

03 mol of chromotropic acid in a dry, finely ground condition are slurried with the alcohol so-

lution for half an hour and the reaction product is then dried at 65 to 70° C. The product obtained in a dry weight of 23.66 grams is a slightly gummy, dark brown powder and is the di-triethanolamine salt.

The product when substituted for the diethanolamine treated chromotropic acid of Example I produces a dry mix which when used in electrolytic recording gives a blue-purple record.

Example IV

.075 mol of diisopropanolamine are dissolved in .574 mol of morpholine.

.574 mol of morpholine.

.10 mol of chromotropic acid in a dry, finely ground condition are slurried with the morpholine solution. The product is then treated at a temperature of about 70° C. A product having a dry weight of 74.04 grams and dark gray in color is thus obtained. The product appears to be a mixed salt of diisopropanolamine and morpholine. When substituted for the chromotropic acid-diethanolamine salt of Example I and the mix used in electrolytic recording, blue-purple records are obtained.

Example V

The procedure is the same as in Example I except that the chromotropic acid is replaced by 1-hydroxy-8-amino-naphthalene-6.7-disulfonic acid.

Example VI

The procedure is the same as in Example I except that the chromotropic acid is replaced by 2-hydroxy-naphthalene-3.6-disulfonic acid.

Example VII

The procedure is the same as in Example I except that the chromotropic acid is replaced by 1,7-dihydroxy-naphthalene-3.6-disulfonic acid.

Various modifications of the invention will occur to persons skilled in the art and I therefore do not intend to be limited in the patent granted except as required by the prior art and the appended claims.

I claim:

1. A storage-stable dry mix for producing electrolytic recording solutions containing as its essential components a diazo amino compound capable of yielding a diazonium compound under the influence of an electrolytic recording current, a water soluble inorganic salt as the electrolyte in an amount to insure passage of the electrolytic recording current and a sufficient quantity of a preformed salt of a naphthol sulfonic acid to

couple with the diazonium compound when formed to produce an azo dye said preformed salt having the following constitution:

in which R is a member of the class consisting of hydrogen, amino and acylamino, m is a number from 1 to 3, n is a number from 1 to 2, and Y is a quaternary ammonium radical selected from the class consisting of monoethanol-ammonium, diethanol-ammonium, triethanol-ammonium, and di-isopropanol-ammonium, said composition when dissolved in water having a pH on the alkaline side any inorganic alkali present being in an amount not greater than 2 grams per liter of recording solution.

2. A storage-stable dry mix for producing electrolytic recording solutions containing as its essential components the diazo amino compound of diazotized naphthionic acid and diethanolamine capable of yielding a diazonium compound under the influence of an electrolytic recording current, a water soluble inorganic salt as the electrolyte in an amount to insure passage of the electrolytic recording current, and a sufficient quantity of a preformed diethanolamine salt of chromotropic acid to couple with the diazonium compound when formed to produce an azo dye, said composition when dissolved in water having a pH on the alkaline side any inorganic alkali present being in an amount not greater than 2 grams per liter of recording solution.

3. A fibrous sheet material impregnated with an aqueous solution of the composition of claim 1.

4. A fibrous sheet material impregnated with an aqueous solution of the composition of claim 2.
